UNITED STATES PATENT OFFICE.

RICHARD G. TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

SIDE-SLIPPING WEFT DETECTOR.

Application filed May 4, 1927. Serial No. 188,824.

This invention relates to weft detectors for looms and it is the principal object of the invention to provide a simple and inexpensive weft detector more particularly of the side slipping type wherein a single spring is effective not only to cause side slipping of the detector to indicate weft exhaustion but also to restore said detector to normal position after a non-indicating movement.

When weft detectors are applied to the usual form of multi-color weft replenishing mechanisms it is customary to provide an actuating lever which floats on the top of a vertically reciprocating rod. At indication of weft exhaustion downward movement of the lever is interrupted so as to initiate replenishment but when sufficient weft is present the actuator lever is free to move downwardly without interruption. Also, on this type of replenishing mechanism, it is necessary to withdraw the feeler on the transferring pick of the loom to clear the path for the incoming bobbin and to prevent repetition of indication of weft exhaustion. It is a further object of my invention to provide a detector of a single piece of material formed to cooperate with the actuator lever and the withdrawing means and also having a weft engaging detecting surface, said detector being held in place by a single spring.

It is a further object of my invention to provide a detector wherein the axis of the resilient element for the detector assumes three different forms, the first being the form when the detector is in normal or inactive position, the second corresponding to the non-indicating but detecting position of the detector, and the last being the form assumed when the detector is in indicating position.

It is a further object of my invention to form the detector wire in such a way that the same will cooperate with the withdrawing means to move the control part of the detector from under the actuator lever in such a way as to insure proper withdrawal to prevent slipping or accidental movement of the detector away from the withdrawing means.

With these and other objects in view which will appear as the description proceeds, my invention resides in the combination and arrangement of parts hereinafter described and set forth in the claims.

In the accompanying drawings, wherein a convenient embodiment of my invention is shown,

Fig. 1 is a top plan view of a weft detector showing the same in contact with a sufficient supply of weft in full lines and showing the same in normal inactive position in dotted lines, parts of the structure being removed and others being shown in section for the sake of clearness.

Fig. 2 is an end elevation looking in the direction of arrow 2, Fig. 1, parts being in section,

Fig. 3 is a vertical section on line 3—3 of Fig. 1,

Fig. 4 is an enlarged detailed section on line 4—4 of Fig. 1, and,

Fig. 5 is a view similar to Fig. 1 but showing the detector moved to indicating position in contact with a bobbin carrying an insufficient supply of weft, the feeler being indicated in withdrawn position in dotted lines.

Referring to the drawings I have provided a feeler stand 10 having a vertical slot 11 to receive the outer end of an actuating lever 12 which is given a downward movement on each detecting beat of the loom. The manner in which the lever 12 is connected to the replenishing mechanism is set forth more fully in the patent to Ryon No. 1,030,748 to which reference may be had. The transfer arm 13 is mounted on a fixed stud 14 and has a depending arm 15 for a purpose to be set forth.

The stand 10 has bolted thereto an adjustable feeler bed 20 which is provided with a rib 21 on which rests a cap 22. Said rib 21 is provided at the rear part thereof with the surface 23 and at the forward end thereof with another surface 24, said surfaces 23 and 24 being lower than the top of the rib 21 and acting as guides for the detector 25. The rib 21 is formed with a shoulder 26 adjacent the surface 23 to serve as a stop for the detector. By means of bolt 27 extending through slot 28 in the bed 20 vertical adjustment of the detector may be effected and by means of slot 29 formed on the stand 10 horizontal adjustment of said detector may be obtained.

The detector 25 is formed of a single piece of wire the rear end of which is bent as in Fig. 1 and provided with a roughened yarn

engaging surface 30. Said detector extends between and is held against improper vertical displacement by the bed 20 and cap 22, the space between the cap and the surfaces 23 and 24 being just sufficient to permit free lateral movement of the detector. The detector extends forwardly of the bed and may have a bent portion 31 which terminates in a forwardly extending portion 32. The withdrawing part 33 extends substantially parallel to the bobbin B in the shuttle S and is perpendicular to the plane in which the arm 15 moves. From the withdrawing portion 33 the detector extends rearwardly as indicated at 34 and may have a part bent back on itself as at 35 and another portion 36 constituting the controller for the actuator.

In order to hold the detector in normal position I provide the cap 22 with an upward standing lug 40 through which extends a holding screw 41 shown more particularly in Fig. 4. Threads of said screw are of such a pitch as to receive the coils of a helical spring 42. The left end of said spring as viewed in Fig. 1 receives the portion 35 of the detector and is held in position frictionally by the coils of the spring. By turning the spring 42 with respect to the threads of the screw 41 the said spring may be adjusted toward or from the actuator lever 12. The feeler stand has a shelf 50 on which the detector parts 35 and 36 may slide.

Under normal conditions the parts will be in the position indicated in dotted lines in Fig. 1 with the roughened end 30 of the detector in its rearmost position to be engaged by the advancing supply of weft and with the controller end 36 resting on the shelf 50 under the actuator lever 12. The spring 42 will be proportioned to hold the detector against the shoulder 26 and the arm 15 will be in the position indicated in Figs. 1 and 2.

So long as sufficient weft is present the detector will be held against lateral movement along the bobbin and will move forwardly from the dotted to the full line position shown in Fig. 1, thereby withdrawing the controller end 36 from under the actuator lever 12 to permit the latter to descend uninterruptedly. Under these conditions the spring will be given the form substantially the same as indicated in full lines in Fig. 1 wherein the ends of the spring are substantially parallel but offset from each other.

When insufficient yarn for continued weaving remains on the bobbin B the spring will act to cause said detector to slide along the bobbin to the position indicated in Fig. 5. Under these conditions the spring will be bent somewhat as indicated in Fig. 5 but the controller end 36 will remain under the actuator lever 12 to interrupt the downward movement of the latter and thus initiate replenishment. As the lay recedes the spring will straighten out to the position indicated in dotted lines

in Fig. 1 to restore the detector to normal position against the shoulder 26. The controller end 36 will be of sufficient length to remain under the actuator lever when the spring assumes the position indicated in Fig. 5.

On a subsequent pick when transfer takes place the arm 15 will be moved to the left as viewed in Fig. 2 toward withdrawing portion 33 and will engage the latter to move the controller end 36 forwardly from under the actuator lever 12. Said arm will engage the part 32 of the wire detector so that the latter will form with the withdrawing portion 33 a bend or corner which will insure proper withdrawal of the controller from the actuator. At the same time the detector will be moved out of the path of the incoming bobbin. The position which the parts assume at the time of withdrawing is indicated in dotted lines in Fig. 5.

From the foregoing it will be seen that I have provided a very simple weft detector wherein a single wire engages the surface to be detected, cooperates with the actuator, is engaged by the withdrawing means and affords attaching means for a spring which serves to hold the detector in normal position. It will further be seen that I have provided a detector wherein a coil spring has one end anchored or secured with respect to the feeler support and the other end freely movable and attached to a detector, said spring yielding so as to bend its axis when indicating weft exhaustion and bending to produce an offset in its axis to permit forward yielding of the detector on non-indicating beats of the loom.

As shown herein the normal position of the spring is with the axis thereof in a substantially straight line, this axis being deformed to assume two different shapes depending upon whether the feeler is or is not indicating, the axis of the spring receiving a compound deflection on non-indicating detecting beats and a simple deflection on indicating beats. On non-indicating beats certain of the coils will be expanded or placed under tension on the front side of the spring and certain other coils will be placed under a similar strain on the rear side of the spring, but on indicating beats the coils which will be stretched apart will lie on one side of the spring. I do not wish to be limited to the form of the spring set forth nor to the shapes which the axis thereof assumes in the varying positions which the detector assumes, as similar results can be attained from springs the axes of which are not necessarily the same as that set forth in dotted lines in Fig. 1.

It will be noted by reference to the drawings that as the feeler moves forwardly the spring 42 resists deflection and tends to move the controller end 36 under the actuator lever, this being the action of course which is relied upon to move the notched end 30 along

the bobbin to detect. At the time of transfer the rear end 30 is moved in advance of the bobbin and is therefore not restrained by the yarn with the result that the controller end 36 would move rearwardly under the actuator lever 12 to repeat the indication were such action not restrained by the forwardly extending portion 32 of the wire being in contact with the depending arm 15 on the transferer. 10 The parts, when the feeler is fully withdrawn by the transferer, are as shown in dotted lines in Fig. 5 where it will be seen that the controller is out of the path of the actuator.

I claim:

- 15 1. In a side slipping weft detector for looms having a detecting element which moves forwardly without side slipping movement when sufficient weft is present but which slides along the bobbin at substantial weft exhaustion a stand for said detector, and a resilient member interposed between the stand and the detector to hold the detector normally yieldingly in detecting position, said mounting comprising a helically coiled spring 25 which is given a compound deflection on non-indicating detecting movements of the detector and is given a simple deflection on indicating movements of the detector, said spring acting to return the detector to normal position.
- 30 2. In a side slipping weft detector for looms having a detecting element which moves forwardly without side slipping movement when sufficient weft is present but which slides along the bobbin at substantial weft exhaustion, a stand for the detector element, a coil spring secured at one end thereof to the stand and extending substantially parallel to the surface being detected, means defining a connection between the detector element and the other end of the spring, said spring acting to hold the detector element normally in detecting position and yielding to bend the axis thereof forwardly on non-indicating 40 detecting beats of the loom and yielding in another direction to bend the axis in the opposition direction on an indicating movement of the detector element, said spring acting to return the detector to normal position.
- 45 3. In a side slipping weft detector for looms having a detecting element which moves forwardly without side slipping movement when sufficient weft is present but which slides along the bobbin at substantial weft exhaustion, a stand to support the detector element, a coil spring fastened at one end to the stand and at the other end to the detector element and tending to hold the latter in normal detecting position, the axis of the spring extending substantially parallel to the surface being detected, said spring yielding forwardly on non-indicating detecting beats of the loom to give the axis of the spring a compound deflection and said spring bending rearwardly 55 on indicating movements of the detector to

give the axis a simple deflection, said spring acting to return the detector to normal position.

4. In a side slipping weft detector for looms having a detecting element which moves forwardly without side slipping movement when sufficient weft is present but which slides along the bobbin at substantial weft exhaustion, a stand to support the detector element, a coil spring having one end secured to the detector element and the other end secured to the stand in fixed position, said spring being given a lateral forward deflection on non-indicating detecting movements of the detector and being given a rearward lateral movement on indicating movements of the detector, said spring acting to return the detector to normal position.

5. In a side slipping weft detector for looms having a detecting element which moves forwardly without side slipping movement when sufficient weft is present but which slides along the bobbin at substantial weft exhaustion, a stand to support the detector element, a spring secured at one end to the stand and at the other end to the detector element, said spring having the normal axis thereof substantially parallel to the surface being detected and being deflected to one side of the normal axis on non-indicating detecting movements of the detector element and being deflected to the other side of the normal axis on indicating movements of the detector, said spring acting to return the detector to normal position.

6. In a side slipping weft detector for looms having a detecting element which moves forwardly without side slipping movement when sufficient weft is present but which slides along the bobbin at substantial weft exhaustion, said detector comprising a single piece of wire formed at its rear end to enter coils of yarn on the bobbin and to slide along a denuded bobbin, an actuator to cooperate with a portion of the wire of which the detector is formed, a member movable forwardly at the time of transfer, said detector having portions thereof located in front of and normally out of contact with the member and bent at right angles to form a corner into which a portion of the member extends when moved forwardly away from the actuator to withdraw the detector, said member lying between the corner in the detector and the actuator.

7. In a side slipping weft detector for looms having a detecting element which moves forwardly without side slipping movement when sufficient weft is present but which slides along the bobbin at substantial weft exhaustion, said detector comprising a single piece of bent wire one end of which is formed to cooperate with the surface to be detected and the other end of which is formed as a controller, an actuator to be controlled by the

controller, a support for the detector, a coil spring having the normal axis thereof substantially parallel to the surface being detected and held at one end to said stand and secured at the other end thereof to said detector adjacent the controller end, said spring yielding in one direction with respect to the normal axis thereof when the detector has a non-indicating detecting movement to move the controller end of said detector out of controlling position for the actuator and the axis of said spring assuming another position with respect to the normal axis thereof when the detector slides along a denuded bobbin to leave the controller end thereof in controlling position for the actuator.

8. In a side slipping weft detector for looms, a stand, a detector formed of a single piece of wire extending through and supported by said stand, said wire being formed on the rear end thereof to have holding engagement of a sufficient supply of weft to be moved forwardly without longitudinal movement with respect to the bobbin as the supply of weft varies but having a longitudinal movement along a bobbin having insufficient weft, an actuator, a guide for the actuator having a shelf, the forward end of said wire of which the detector is made resting on the shelf and normally lying in the path of the actuator, and a helical coil spring having one end held to the stand in fixed position and having the other end secured to the detector at a point adjacent the actuator and shelf, said spring having a normal axis thereof parallel to the surface being detected and yielding forwardly as the detector is advanced by a sufficient supply of weft to withdraw the end of the detector from the path of the actuator and said spring yielding in another direction when the detector moves along a substantially exhausted bobbin so that the end of the detector on the shelf will remain in the path of the actuator, said spring acting to restore the detector to normal position.

9. In a side slipping weft detector for looms having a detecting element which moves forwardly without side slipping movement when sufficient weft is present but which slides along the bobbin at substantial weft exhaustion, said detector comprising a single piece of wire formed at its rear end to enter coils of yarn on the bobbin and to slide along a denuded bobbin, an actuator to cooperate with a portion of the wire of which the detector is formed, a member movable forwardly at the time of transfer, means tend-

ing to move the detector angularly whenever said detector is moved forwardly, said detector and member being so formed that when said member engages the detector to withdraw the same said detector will be held against the action of the means which tends normally to give said detector an angular movement, whereby that portion of the detector which cooperates with the actuator will be moved relatively to said actuator.

10. In a side slipping weft detector for looms having a detecting element which moves forwardly without side slipping movement when sufficient weft is present but which slides along the bobbin at substantial weft exhaustion, said detector comprising a single piece of wire formed at its rear end to enter coils of yarn on the bobbin and to slide along a denuded bobbin, an actuator to cooperate with a portion of the wire of which the detector is formed, a member movable forwardly at the time of transfer, means tending to move the detector angularly whenever said detector is moved forwardly, said detector having a portion extending in the path of the member to be engaged by the latter, and a device effective when said member engages the detector to prevent angular movement of the latter to thereby insure movement of that end of the detector which cooperates with the actuator relatively to said actuator.

11. In a side slipping weft detector for looms having a detecting element which moves forwardly without side slipping movement when sufficient weft is present but which slides along the bobbin at substantial weft exhaustion, said detector comprising a single piece of wire formed at its rear end to enter coils of yarn on the bobbin and to slide along a denuded bobbin, an actuator to cooperate with a portion of the wire of which the detector is formed, a member movable forwardly at the time of transfer, means tending to move the detector angularly whenever said detector is moved forwardly, said detector having a portion extending in front of the member and having parts to engage said member to prevent angular movement of the detector relatively to the plane of movement of the member when the latter moves forwardly, whereby that portion of the detector which cooperates with the actuator is moved out of the path of the latter when the detector moves forwardly.

In testimony whereof I have hereunto affixed my signature.

RICHARD G. TURNER.
